UNITED STATES PATENT OFFICE.

DAVID STEWART, OF PHILADELPHIA, PENNSYLVANIA.

DESIGN FOR A CAKE.

SPECIFICATION forming part of Design No. 23,955, dated January 15, 1895.

Application filed December 8, 1894. Serial No. 531,286. Term of patent 7 years.

To all whom it may concern:

Be it known that I, DAVID STEWART, a citizen of the United States, residing in the city and county of Philadelphia, in the State of Pennsylvania, have invented and produced a new and original Design for Cakes, of which the following is a specification, reference being had to the accompanying drawings illustrative of the same.

10 My design is embodied in the cake represented in top plan view in Figure 1, and in central longitudinal section in Fig. 2, of the accompanying drawings, and depicted therein as possessing in plan the approximate conventional outline of an acorn, and marked as to

15

a zone or band extending transversely of its face in the region of its broader end, with cross hatching markings, as shown, and the characteristics described constitute the essential features of my design for a cake. 20

What I claim is—

The design for a cake, substantially as herein shown and described.

In testimony that I claim the foregoing as my invention I have hereunto signed my name 25 this 22d day of November, A. D. 1894.

DAVID STEWART.

In presence of—

F. NORMAN DIXON,
THOS. K. LANCASTER.
